CLOSURE FOR BOOTS

Francis J. Shields, Bombay, N. Y.

Application December 29, 1941, Serial No. 424,719

3 Claims. (Cl. 36—50)

This invention relates to new and useful improvements in a boot.

More specifically, the invention proposes the construction of a boot or shoe characterized by a shoe body having a flexible sole and upper, preferably constructed of sheepskin arranged in a manner to have its fleecy material directed inwards to engage the surfaces of the foot when passed into the boot.

It is a further object of this invention to provide the boot upper with a front opening adapted to be closed by means of a flexible tongue constructed of sheepskin material having its fleece material directed outwards to add to the decorative appearance of the boot.

Still further it is proposed to provide the boot upper with a strap having one end attached to one side of the upper and engageable with a buckle mounted on the other side of the upper, and arranged in a manner to close the front opening and simultaneously hold the tongue in position there-across.

It is further proposed to provide a means for adjustably mounting the end of the strap and the buckle in position on the upper in such a manner that the position of the belt may be adjusted upwards and downwards to engage across the front portion of one's foot at a desired position so as not to interfere with normal walking steps.

For further comprehension of this invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a boot constructed in accordance with this invention.

Fig. 2 is a perspective view of the boot with the closure strap and tongue moved to an open position.

Fig. 3 is an enlarged detailed view of the buckle, per se.

Fig. 4 is a horizontal sectional view taken through the upper of a boot constructed in accordance with a modification of this invention.

Fig. 5 is an elevational view looking in the direction of the line 5—5 of Fig. 4.

Fig. 6 is a horizontal sectional view taken substantially on the line 6—6 of Fig. 5.

Fig. 7 is a perspective view of the plate appearing in Fig. 6.

Fig. 8 is an elevational view looking in the direction of the line 8—8 of Fig. 4.

The boot according to this invention, comprises a flexible boot body 10 having a flexible sole 11 and a flexible upper 12. The sole 11 and upper 12 are preferably constructed of sheepskin having the fleecy material directed inwards to engage the surfaces of the foot and provide greater warmth. The bottom face of the sole 11 is provided with a layer of rubber 13 adding to the strength of the sole construction and permitting the shoe to be worn upon the street. The front of the upper 12 is provided with an opening 14 which permits the upper of the shoe to be opened to facilitate the engagement of the foot therein.

A flexible tongue 15 has its bottom end securely attached to the vamp portion of the upper 12 and is normally projected upwards over the front opening 14. The tongue 15 has its fleecy material directed outwards for the purpose of adding to the decorative appearance of the shoe 10.

A loop 16 is secured to the back of the upper 12 and is adapted to be engaged by one's finger for the purpose of providing a grip to facilitate the pulling of the shoe into position on the foot. A strap 17 has one of its ends secured to the upper 10 on one side of the opening 14 and is provided at its free end with a plurality of openings 18. A conventional buckle 19 is mounted on the upper 12 on the opposite side of the opening 14. The buckle 19 has a pivotally mounted tongue 20 adapted to be selectively engaged with one of the openings 18 in the conventional manner for securing the end of the strap to the buckle 19.

The buckle 19 is securely attached to a piece of leather 21 by means of stitches 22 on opposite sides of the tongue 20. The piece of leather 21 is then securely attached to the side of the upper 12 by means of a line of stitches 23 to securely mount the buckle in position.

It is believed that the manner of positioning the shoe upon the foot is obvious and further details are not believed necessary.

According to the modification of the invention shown in Figs. 4—8 the construction of the shoe is similar to that previously described, except for the provision of means for adjustably attaching the end of the strap 17 and the buckle 19' to the sides of the upper 10 so that these attached portions may be moved vertically upwards and downwards to adjust the position of the strap 17' to engage across a desired area

of the foot so as not to interfere with normal walking.

The attachment of the buckle 19' is accomplished by projecting a stud 24 from a portion of the buckle 19' and passing the stud into the space 25 between the piece of leather 21 and the side of the upper 10. A metallic member 26 is disposed within the space 25 and is provided with a longitudinal opening 27 aligned with a complementary slot 28 formed in the piece of leather 21. The stud 24 passes through the opening 27 in the loop 26 and has a head engaging the back face of the member to prevent disengagement of the stud 24 from the opening 27. The front edge of the opening 27 is provided with a plurality of semi-circular cutouts 29 into which the stud 24 is adapted to be selectively engaged for the purpose of preventing relative movement of the stud 24 and metal member 26. In the engaged position of the strap 17 with the buckle 19' the pressure upon the strap tends to draw the stud 24 into one of the semi-circular cutouts 29, preventing movement. In the released condition of the strap 17 from the buckle 19' it is possible to move the buckle 19' rearwards of the upper 12 to disengage the stud 24 from its respective semi-circular cutout 29 to be moved to an adjusted position along the length of the opening 27.

The attachment means for the end of the strap 17' is similar to the means for attaching the buckle 19'. This is accomplished by engaging the end of the strap 17' about a strip of metal material 30 and securing the doubled over end in position by a line of stitches 31. A stud 32 projects from the piece of metal 30 which passes through a slot 28 formed in the piece of leather 21 used for securing the piece of metal 26 in position upon the side of the shoe upper. The stud 32 of the end of the strap 17' is selectively engageable with one of a plurality of semi-circular cutouts 29 formed along the front edge of an opening 27 formed in the piece of metal 26.

It is to be understood that it is only possible to adjust the position of the strap 17' and buckle 19' in a disengaged position of these members, permitting their attached portions to be moved slightly rearwards relative to the keeper 12 to disengage their respective studs from their respective semi-circular cutouts permitting the studs to be moved along the length of the openings 27. In other respects this form of the invention is similar to the previous form.

While I have illustrated and described the preferred embodiments of the invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A boot having an open front closed by means of a tongue extended upwards from the vamp portion of said boot and a strap extendable across said tongue to be engaged with a complementary buckle for holding said tongue in position, a plate

mounted on the outer end of said strap, a stud projecting from said plate, a stud projecting from said buckle, and means for vertically adjustably mounting said studs on said boot on opposite sides of said tongue so that the position of said strap and buckle may be adjusted vertically to extend across one's foot at a desired position so as not to interfere with normal walking steps.

2. A boot having an open front closed by means of a tongue extended upwards from the vamp portion of said boot and a strap extendable across said tongue to be engaged with a complementary buckle for holding said tongue in position, a plate mounted on the outer end of said strap, a stud projecting from said plate, a stud projecting from said buckle, and means for vertically adjustably mounting said studs on said boot on opposite sides of said tongue so that the position of said strap and buckle may be adjusted vertically to extend across one's foot at a desired position so as not to interfere with normal walking steps said vertically adjustable means, comprising pieces of leather having their edges secured to said boot on opposite sides of said tongue and formed with vertical slots, and metallic members disposed in the spaces between the adjacent faces of said boot and pieces of leather and formed with elongated openings aligned with said slots, said studs being passed through said aligned slots and openings and having enlarged heads abutting the back faces of said metallic members so that said studs may be moved to desired positions along the length of said aligned slots and openings.

3. A boot having an open front closed by means of a tongue extended upwards from the vamp portion of said boot and a strap extendable across said tongue to be engaged with a complementary buckle for holding said tongue in position, a plate mounted on the outer end of said strap, a stud projecting from said plate, a stud projecting from said buckle, and means for vertically adjustably mounting said studs on said boot on opposite sides of said tongue so that the position of said strap and buckle may be adjusted vertically to extend across one's foot at a desired position so as not to interfere with normal walking steps said vertically adjustable means, comprising pieces of leather having their edges secured to said boot on opposite sides of said tongue and formed with vertical slots, and metallic members disposed in the spaces between the adjacent faces of said boot and pieces of leather and formed with elongated openings aligned with said slots, said studs being passed through said aligned slots and openings and having enlarged heads abutting the back faces of said metallic members so that said studs may be moved to desired positions along the length of said aligned slots and openings, said metallic members being formed with semi-circular cutouts adjacent the inner edges of said openings into which said studs may have their shanks selectively engaged before said buckle and strap are engaged so that when said buckle and strap are engaged said shanks will retain their engaged position with the selected cutouts to retain said strap and buckle in their adjusted positions.

FRANCIS J. SHIELDS.
